ROLL FOR CALL

PATENT OFFICE

0,221 per cento

John D. Hollingsworth
Application September 1, 1911
1 Claim.

1 Claim. (Cl. 19—112)

This invention relates to the fibre-handling surfaces of the cylinders, doffers, workers, strippers, licker-in, feed, fancy and other rolls of carding or garnett machines, for handling synthetic fibre cut into staple lengths, such as "rayon," "nylon," etc., or natural fibres, such as wool, cotton, etc.,

Prior to this invention it has been difficult to card synthetic fibres especially, due to the fibres having a tendency to cling to the teeth of the various rolls. This caused the fibres to mat and choke the fibre-handling surfaces of the various rolls, resulting in the production of a very uneven fleece or web as removed from the main cylinder by the doffers.

The above condition made it extremely difficult to mix the various kinds of fibres, due to one clinging to a greater or lesser extent than another.

One object of the present invention is to provide the fibre-handling rolls with fibre-contacting surfaces which will materially reduce or entirely eliminate the clinging of the fibres to the teeth of the various rolls.

Another object of the invention is to improve the efficiency of the fibre-handling surfaces so that the staple, or fibre, or mixtures of various kinds thereof, are carded, combed, straightened, and laid parallel, etc. in a greatly improved state.

In the accompanying drawing:

Fig. 1 is a partial longitudinal sectional view through a roll clothed in accordance with the present invention:

Fig. 2' is a transverse sectional elevation taken on the line 2—2 Fig. 1.

Figs. 3 and 4 are fragmentary views similar to

Figs. 5 and 6 are fragmentary views similar to Fig. 2 and showing variations in the clothing;

Fig. 7 is a view similar to Fig. 1, showing a variation in the arrangement for attaching the clothing to the roll.

As shown in Fig. 1, the roll 1, which may be the cylinder or any of the previously noted working rolls of a garnett or carding machine, comprises a foundation cylinder 2 having a fibre-contacting surface 3. The fibre-contacting surface 3 is composed of circumferentially-extending ribs 4 alternating with circumferentially-extending grooves 5.

Normally, in a carding roll the outer or peripheral edge 6 of each rib 4 is discontinuous, i.e., each rib is provided with a multiplicity of teeth arranged with the tips 7 of the teeth equi-

1. 19—112) distantly spaced from the axis of the roll throughout the length and circumference of the roll, and which collectively constitute the fibre-contacting surface 3 of the roll. Between successive teeth tips 1, circumferentially of the roll, the teeth are provided with gullets 8 which extend inwardly into the ribs 4. It is in these gullets that the fibres become matted which causes choking of the surface 3 of the roll and prevents the tips 1 of the teeth from properly engaging and working the fibres into a parallel relationship to each other.

In accordance with the present invention, alternate ribs 4' preferably are formed with continuous circumferentially-extending outer edge surfaces 10, which, as shown in Fig. 2, may be disposed on the same radius as the tips 7 of the teeth of the ribs 4 or, as shown in Fig. 3, may be disposed on a radius slightly greater than that of the tips 7. Preferably, however, the continuous surfaces 10 of the ribs 4' are formed on a radius slightly less than that of the tips 7, as clearly shown in Fig. 4.

25 Instead of having the plain-edge ribs in alternating relation to the toothed-edge ribs in successive groups axially of the roll, wherein each group includes one plain-edge rib and one toothed-edge rib, the groups may be arranged with unequal numbers of plain and toothed-edge ribs in each group, for example, as shown in Fig. 5, each group may include one toothed-edge rib and two plain-edge ribs, with the plain-edge ribs disposed immediately adjacent each other. As shown in Fig. 6, each group may include one plain-edge and two or more toothed-edge ribs, with the toothed-edge ribs, in this instance, disposed immediately adjacent each other. Obviously, any suitable combination as to numbers and positioning of the ribs in each group may be provided in the handling of different kinds of fibres, for example, longer fibres may require a greater number of plain-edge ribs, whereas shorter fibres may require a greater number of toothed-edge ribs than there are plain-edge ribs. 40 45 However, for general purposes, groups including one plain-edge rib and one toothed-edge rib have in practice given very satisfactory results.

As a matter of convenience, the clothing is in the form of a wire of a cross-section similar to that shown in Fig. 1, and includes a substantially rectangular base 11 having a flat inner edge surface 12 adapted to bear against the outer peripheral surface 13 of the foundation cylinder 2. In that form of the invention shown in Fig. 1, for example, the wire includes a blade

portion 14 having one side face continuous with a side face 15 of the base 11, and which is disposed substantially at right angles to the flat edge 12 of the wire. The blade 14 is of relatively narrower width than the base 11, with that end of the blade disposed adjacent the base 11 inset with respect to the second longitudinal surface 16 of the base 11 providing a longitudinal recess 17 along the full length of the wire. As shown in Fig. 1, the blade tapers downwardly towards its outer edge 6, which outer edge preferably is disposed at right angles to the side face 15 and parallel to the inner edge 12.

The clothing wires, depending upon the grouping, are secured to the roll at one end thereof in side by side relation to each other with the shallow side 16 of the base of one wire in laterally abutting relation to the deep side face 15 of the next adjacent wire. The wires are then wound in successive convolutions on the outer surface 13 of the roll 2 from end to end of the roll, and the second end of each wire is then secured to the roll in any suitable manner, in this arrangement, the recesses 17 of the respective wires constituting the grooves 5 in the fibre-engaging surface of the roll. The flat side 15 of one wire and the outwardly tapering side 18 of the blade 14 of the next adjacent wire forming the side walls of each groove, and the inclined surface 19 of the top of the base 11 of each wire constituting the base of the groove 5.

Cross-sectionally the toothed and plain-edge wires preferably correspond, and in the toothed-edge wire the gullets 8 are formed in the blade

portion 14 of the wire, as clearly shown in Figs. 1 and 2.

If alternating plain and toothed-edge ribs are desired, the convolutions are formed with two wires or multiples of two in side by side relation to each other, for groups corresponding to Figs. 5 and 6, three wires or multiples of three with two of one kind and one of another in the proper relationship to each other are wound in successive convolutions on the face of the roll.

If desired, instead of the wire being surface-wound on the roll, the roll may be provided with axially-spaced spiral grooves 20, in which the base 11 of the wire may be laid and secured, as clearly shown in Fig. 7.

I claim:

A roll having a fibre-contacting surface composed of alternately arranged circumferentially extending ribs and grooves formed by a series of wires of corresponding cross-sectional contours and each including a base of predetermined width seated on the roll and an upstanding blade of relatively narrower width projecting from said base, with the blade of one or more of the wires of the series provided with fibre engaging points formed in the outer edge thereof and the blade of each remaining wire of the series having a substantially smooth outer edge devoid of said teeth, said series of wires being disposed on said roll in interwound spiral convolutions providing said surface with intermingled plain and toothed-edged ribs of equal widths separated by grooves of equal relatively greater widths throughout said surface.

JOHN D. HOLLINGSWORTH.
